UNITED STATES PATENT OFFICE.

HENRY F. SCHMIDT, OF SWARTHMORE, PENNSYLVANIA, ASSIGNOR TO WESTINGHOUSE ELECTRIC AND MANUFACTURING COMPANY, A CORPORATION OF PENNSYLVANIA.

TURBINE-BLADE STRUCTURE.

Application filed April 16, 1920. Serial No. 374,373.

To all whom it may concern:

Be it known that I, HENRY F. SCHMIDT, a citizen of the United States, and a resident of Swarthmore, in the county of Delaware and State of Pennsylvania, have invented a new and useful Improvement in Turbine-Blade Structures, of which the following is a specification.

This invention relates to turbines and it has for an object to produce a novel turbine wheel and bucket suitable for impulse turbines.

More specifically the object of my invention is to produce a new and improved turbine wheel arrangement in which the passages for motive fluid are formed between or in blades or buckets which are supported against centrifugal force in compression instead of in tension.

These and other objects which will be made apparent throughout the further description of my invention are attained by means of apparatus embodying the features of my invention herein described and illustrated in the drawings accompanying and forming a part hereof.

My invention contemplates a turbine wheel in which the working elements are mounted on the inner periphery of a cylindrical or overhanging flange, whereby these elements are effectively supported in compression against centrifugal force. This method of securing or mounting the elements greatly simplifies the securing or mounting means. A further advantage of such a construction is that the elements may be made of relatively light material, such, for example, as pressed steel or bronze and nested together on the inner periphery of the flange.

My invention also contemplates a new and improved impulse bucket adapted for this construction.

In the drawings: Fig. 1 is a diagrammatic sectional view, along the line 1—1 of Fig. 2, of a turbine wheel arrangement embodying the features of my invention.

Fig. 2 is a sectional view along the line II—II of Fig. 1.

Fig. 3 is a perspective view of one of the buckets illustrated in operative position in Figs. 1 and 2.

In Fig. 1, I have illustrated a turbine wheel 5 as mounted on the overhanging end of a shaft 6. However, a shaft supported

on both sides of the wheels 5 may be provided, if desired. The turbine wheel illustrated is provided with an overhanging cylindrical flange or drum 7 on the inner periphery of which the working elements are mounted. Preferably the flange 7 defines an internal channel 7' within which are located the bucket-forming elements hereinafter referred to.

The working elements illustrated consist of sheet metal impulse buckets 8 of the Pelton type, one of which is shown in detail in Fig. 3. These buckets are nested together, as shown in Fig. 2, so as to form a series of semi-circular motive fluid passages which overlap each other and are inclined to the inner periphery of the flange 7. As shown, motive fluid is delivered at high velocity to one side of the buckets 8 by means of a nozzle 10 (shown in dotted lines in Fig. 2). The impulse of the jet of motive fluid striking the buckets, and the reaction due to the deflection of the jet around the semi-circular passage produce the force which causes the wheel 5 to rotate.

I have shown a reversing chamber 11 for receiving the motive fluid discharged from the inner side of the buckets 8 and for redirecting it into the buckets at a point farther along on the inner periphery of the flange 7. If desired, a plurality of reversing buckets may be employed so as to repeat the redirecting of the motive fluid into the buckets. This method of extracting the energy of the steam is familiar to those skilled in the art and requires no further description.

In the construction illustrated, the buckets 8 are composed of bucket-forming elements 9 which rest upon one another in the channel 7' and define buckets or passages for the motive fluid. Each bucket-forming element 9 is preferably pressed into scoop form from sheet metal and, as may be seen from Fig. 3, comprises a bottom portion 9' and a semi-circular flange portion 12 terminating in overhanging flanges 12' adapted to rest on shoulders 13, formed on the flange 7 at the sides of the channel 7'. The shoulders 13 are of such a height as to hold the inclined bucket-forming elements, with the semi-circular ends resting at the bottom of the channel 7' and the flanges 12' on the shoulders 13, at the proper inclination to

secure a correct operative position of the buckets as shown in Fig. 2. Also, I show caulking strips 14 extending along with the shoulders 13 which may be crimped over the flanges 12' of the bucket members 9 to secure the latter in place.

The bucket forming element illustrated in Fig. 3 consists of a sheet metal stamping, such as may be made in one or two operations of a press. The bucket elements are shaped so as to automatically nest together when assembled, as shown in Fig. 2. It will be noted that the bucket elements rest against the inner periphery of the flange 7 and that the flanges 12' rest on the internal shoulders 13, consequently the buckets are supported against centrifugal force in compression instead of in tension, as is usually the case. For this reason more elaborate mounting means are unnecessary.

While I have shown my invention in but one form, it will be obvious to those skilled in the art that it is not so limited but is susceptible of various other changes and modifications, without departing from the spirit thereof and I desire therefore, that only such limitations shall be placed thereupon as are imposed by the prior art or as are specifically set forth in the appended claims.

What I claim is:

1. A turbine wheel having an overhanging flange, shoulders on the inner periphery of said flange and sheet metal buckets nested within said flange and supported by the flange and the shoulders.
2. In a turbine, the combination of a rotor provided with an internal bucket-holding channel, a series of contacting buckets in the channel and having their outer ends resting on the bottom of the channel, and a flange portion at the entrance ends of the buckets for supporting the latter with respect to the sides of the channel.
3. In a turbine, the combination of a rotor provided with an internal channel having lateral shoulders and a series of inclined buckets resting at their outer ends on the bottom of the channel and having outwardly

extending flanges at their inner ends to rest on said shoulders.

4. In a turbine, the combination of a rotor having an internal channel, a series of scoop-shaped, sheet-metal buckets in the channel and having their outer ends resting against the bottom of the channel, and overhanging flanges at the inner ends of the buckets for holding them in place with respect to the channel.

5. In a turbine, the combination of a rotor having an internal channel provided with lateral shoulders, a series of inclined sheet-metal buckets in the channel and having their outer ends resting against the bottom of the channel, and outwardly pressed flanges at the inner ends of the buckets which rest on said shoulders.

6. In a turbine, the combination of a rotor having a channel provided with lateral shoulders, a series of buckets having like ends resting against the bottom of said channel, curved flanges at the other ends of the buckets resting on said shoulders, and means on the rotor for holding said first means in place with respect to said shoulders.

7. A turbine bucket element of scoop form having a bottom portion and a curved flange portion terminating in inclined overhanging flanges.

8. A turbine comprising a rotor having a flange defining an internal channel with lateral shoulders, a plurality of buckets composed of bucket elements of scoop form having bottom portions and curved flange portions terminating in overhanging flanges, the bucket elements being disposed in an inclined manner in the channel with the bottom portions resting against the flange and cooperating with the semi-circular flanges to define motive-fluid passageways and with the over-hanging flanges resting on said shoulders, and a nozzle and reversing chamber cooperating with the buckets.

In testimony whereof, I have hereunto subscribed my name this March 30, 1920.

HENRY F. SCHMIDT.
